UNITED STATES PATENT OFFICE

BENJAMIN SPECTOR, OF NEW YORK, N. Y., ASSIGNOR TO GROPPER SPORT APPAREL CO., INC., OF NEW YORK, N. Y., A CORPORATION OF NEW YORK

YARN CARRIER FOR KNITTING MACHINES

Application filed August 22, 1930. Serial No. 477,018.

This invention relates to yarn carriers for knitting machines and more particularly to yarn carriers adapted for use in the production of plated fabric.

5 An object of the invention is to provide a device of the character described which is simple and sturdy in construction, which may be manufactured economically, which is effective under a variety of operating conditions, and which will efficiently accomplish the purposes for which it is intended.

10 A further object is to provide improved means for reversing the position of the yarns in the production of plated fabric on a flat 15 knitting machine.

15 More specifically, it is an object of the invention to provide means to assist the movement of one yarn about another yarn when the direction of the movement of the yarn 20 carriers is reversed in the production of plated fabric on a flat knitting machine.

25 Other objects of the invention will in part be obvious and will in part appear herein-after.

30 The invention accordingly comprises the features of construction, combinations of elements, and arrangement of parts, which will be exemplified in the constructions herein-after set forth and the scope of the application of which will be indicated in the claims.

35 For a fuller understanding of the nature and objects of the invention, reference should be had to the following detailed description taken in connection with the accompanying drawing, in which:

40 Figure 1 is a front view of a portion of a flat knitting machine showing a yarn carrier embodying the invention as it appears when moving in one direction;

Fig. 2 is a similar view showing the yarn carrier as it appears when moving in the opposite direction;

45 Fig. 3 is a top view of the exemplified yarn carrier;

Fig. 4 is a side view thereof, showing certain associated elements;

Fig. 5 is a detail side view illustrating a modified form of construction;

50 Fig. 6 is a detail bottom view of this con-

structure with the part in one position; and

Fig. 7 is a detail bottom view of the construction with the parts in another position.

In the production of plated knit fabric on a flat knitting machine wherein the direction of movement of the yarn carrier and the operating cams is reversed at the end of each course, the relative position of yarns must be correspondingly reversed, and to permit such reversal, there is commonly utilized a member such as shown at 10 which provides a small opening for one of the yarns and provides for the other of the yarns a generally arcuate opening terminating at either side of the small opening, so that upon the reversal of the movement of the guiding member, the yarn extending through the arcuate opening will, due to its lag, pass rearwardly along the entire length of the arcuate opening, so as to occupy a position at the rear of the first yarn. Considerable difficulty has been experienced in the failure of yarn to move with speed and certainty along the course provided by the arcuate opening, and this is particularly the case in the use of relatively thick yarns of irregular width, for example, knotted yarns, such as bouclé yarn and rattiné yarn. This disadvantage is enhanced by the knitting and structural requirements involved in most knitting methods and machines which limit the size and shape of the slot.

With these and other considerations in view, the present invention contemplates the provision of a supplemental guiding member which will cause the yarn to move from one end of the arcuate opening to the other with ease and certainty, and further contemplates the provision of positive means for reversing the position of the yarns. The exemplified yarn carrier comprises a guiding member 10 formed with a small opening 11 adapted to guide a yarn 12 and with an arcuate opening 13 adapted to guide a yarn 14. The member 10 is supported on a suitable frame piece 15 which in the present instance is formed with a supplemental guide opening 16 for the yarn 12. In accordance with the invention, there is pivotally mounted, as by means of a screw 17 at a point in line with and in front of the opening 16, a swinging member 18 formed

at its outer end with an opening 19 for the yarn 14, the distance between the openings 16 and 19 when the member 18 extends to one side, being considerably greater than the 5 distance between the opening 11 and either end of the slot 13. The yarn 12 may extend over a suitable sliding pulley 20 to a spool 21 and the yarn 14 may extend over a suitable sliding pulley 22 to a spool 23.

10 It will accordingly be seen that when the direction of movement of the yarn carrier is reversed, the lag of the yarn 14 will cause the pivoted member 18 to swing to the rear and the tension on the yarn 14 resulting from the 15 movement of the pivoted member, will assure a speedy and direct movement of the yarn 14 from one end to the other of the slot 13; the reversal of this action resulting when the yarn carrier changes its direction of 20 movement at the other end of the machine. The arc through which the opening 19 swings is sufficient to cause an effective pull which will overcome any resistance due to friction of the yarn against the walls of the slot 13, 25 so that the yarn 14 when it is received by the needles will always be at the rear of the yarn 12 and that the danger of the yarn 14 being frictionally held ahead of the yarn 12 with resulting imperfections in knitting, is 30 effectively eliminated.

In certain instances, as when the entering yarn exerts a pull inwardly, suitable means may be provided to limit the movement of the free ends of the pivoted member in a direction toward a member such as 10. Such a result may be obtained, for example, by so constructing the pivoted member that the distance from the axis of the pivot pin to the side edges of the pivoted member is greater 35 than the distance from the axis to its inner edge, and by interposing a protuberance between the inner edge of the pivoted member and the guide opening for the rear yarn. This may be so arranged that the arc of movement of the free end of the pivoted member is a semicircle or less, as desired. One such arrangement is exemplified in Figs. 5, 6 and 7. In this instance, there is shown a swinging member 18a pivotally mounted on a frame 40 piece 15a by means of a screw 17a. The inner surface of the member 18a, as indicated at 24, is so constructed that the distance from its axis to the side edges thereof is greater than the distance from its axis to its inner 45 edge and there is interposed between this inner edge and the guide opening 16a for the inner yarn, a protuberance 25 which, in the present instance, is shown as a part of an annulus 26. As is indicated in Fig. 7, the 50 protuberance 25 limits the inward movement of the outer end of the member 18a.

Since certain changes may be made in the above construction and different embodiments of the invention could be made without departing from the scope thereof, it is 55

intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent, is:

1. In a yarn carrier adapted for use in the production of plated knit fabric, the combination of an outwardly extending arm providing a yarn guide for one yarn, and an arm having its inner end pivotally connected with the outer end of the aforesaid arm and at its outer end providing a yarn guide for another yarn, the free end of said pivoted arm being adapted to swing freely to a position at the rear of said first mentioned yarn guide each time the direction of movement of the yarn carrier is reversed, said free end being formed with an eyelet for said other yarn.

2. In a yarn carrier adapted for use in the production of plated knit fabric, the combination of an outwardly-extending arm providing a yarn guide for one yarn, and means providing a yarn guide for another yarn, the latter guide comprising an arm pivotally connected at its inner end with the aforesaid arm in a transverse vertical plane intersecting the first mentioned arm and having at its free end an eyelet for said other yarn.

3. In a yarn carrier adapted for use in the production of plated knit fabric, the combination with means providing a small opening for the guiding of one yarn and an arcuate slot extending at both sides of said small opening and adapted to guide another yarn, of an outwardly extending arm disposed above the aforesaid means and having an opening for guiding the first-mentioned yarn, and an arm pivotally mounted on the outer end of the outwardly extending arm and having an opening for guiding said other yarn in its outer end at a point adapted to swing beyond each side of said slot, whereby the movement of a yarn from one side of said slot to the other side on the reversal of the yarn carrier will be facilitated.

4. In a yarn carrier adapted for use in the production of palted knit fabric, the combination with means providing a small opening for the guiding of one yarn and an arcuate slot extending at both sides of said small opening and adapted to guide another yarn, of a vertical arm extending upwardly from said means, an arm extending outwardly a short distance from the upwardly extending arm and formed with an opening providing a supplemental guide for said one yarn, means providing a supplemental guide for said other

yarn disposed above said arcuate slot and comprising an arm pivotally connected at its inner end with the outer end of said outwardly extending arm and formed with an opening at its outer end for said other yarn and adapted to accentuate the normal lag of said other yarn to overcome frictional resistance in said arcuate slot.

5. In a yarn carrier adapted for use in the production of plated knit fabric, the combination of means providing a yarn guide for one yarn, means providing a yarn guide for another yarn, the latter guide comprising a pivoted member, the free end of which is adapted 10 to swing to a position at the rear of said first mentioned yarn guide each time the direction of movement of the yarn carrier is reversed, said free end being formed with an eyelet for said other yarn, and means to limit the movement of said pivoted member to confine its movement to an arc not greater than a semi-circle, the inner end of said pivoted member being so constructed that the distance from its pivotal axis to the side edges of the pivoted 15 member is greater than the distance from said axis to the inner edge of the pivoted member, and said limiting means comprising a protuberance carried by the first-mentioned means and disposed inwardly of said pivoted 20 member.

In testimony whereof I affix my signature.
BENJAMIN SPECTOR.
